DESIGN FOR A COMBINED CIGARETTE BOX AND ASH TRAY HOLDER

Abe M. Wolfson, Chicago, Ill.

Application May 22, 1944, Serial No. 113,715

Term of patent 14 years

(Cl. D85—2)

To all whom it may concern:

Be it known that I, Abe M. Wolfson, a citizen of the United States and a resident of Chicago, county of Cook, and State of Illinois, have invented a new, original, and ornamental Design for a Combined Cigarette Box and Ash Tray Holder, of which the following is a specification, reference being had to the accompanying drawing, forming part thereof.

In the drawing:

I claim:

The ornamental design for a combined cigarette box and ash tray holder, substantially as shown.

ABE M. WOLFSON.
